SINGLE TRIGGER MECHANISM

Application filed January 11, 1930. Serial No. 420,094.

This invention relates to improvements in single trigger mechanism for double guns (either of the side-by side or the over-and-under types) in which the barrels may be fired in succession (selectively or otherwise) upon successive pulls of a single trigger.

In order that the aims of the invention hereinafter pointed out, and my improved arrangements for accomplishing these aims, may be more easily understood, it may be stated here that in guns of the double-barrel single-trigger type, difficulty, (unless means are provided for preventing it) is experienced with "doubling", that is accidental and unconscious discharging of the second barrel after the first barrel has been fired due to "involuntary pull". "Involuntary pull" and resulting "doubling" are probably due to the fact that when the trigger is pulled to fire the first barrel, the gun, upon discharge, recoils and the trigger recedes from the finger, whereupon the trigger returns to operative position and upon the rebound forwardly of the gun from the shoulder the trigger reengages the finger which may have followed the gun in its recoil. When the finger is thus reengaged by the trigger, the second barrel may be unintentionally discharged in such rapid succession to the first barrel that the shooter is unconscious of having "doubled", the reports being so close together as to be frequently indistinguishable from one another, or so close that the interval between the reports is almost imperceptible.

The main aim of the present invention is to provide an improved arrangement wherein "doubling" is absolutely and entirely avoided; that is to say, that arrangement is such that there is no possibility of firing the second barrel during the recoil and rebound of the gun due to the discharge of the first barrel.

A further aim of the invention is to provide an improved arrangement having the above mentioned object and wherein "balking" is avoided; that is to say, while the arrangement is such that "doubling", due to involuntary pull, is avoided, the operation of the mechanism is such that the trigger mechanism—after the first barrel is fired—will

advance into operative relation to the sear associated with the second barrel so quickly that a second intentional pull on the trigger before the trigger mechanism has reached the second position cannot take place.

55

A still further aim of the invention is to provide a trigger mechanism of the character described and wherein the lightness of the weight of pull on the trigger to fire the gun is limited only by a sufficiently secure arrangement between the hammers and sears to prevent the second sear from jarring out of engagement with its hammer when the first barrel is fired.

A still further aim of the invention is to provide an improved arrangement where in the weight of any part or parts operating upon the sears is not sufficient to accidentally disengage a sear from its cocked hammer should the gun be jarred as, for example, if the gun were dropped.

A further aim of the invention is to provide a trigger arrangement having the above and other objects, and which is characterized by its simplicity in construction and its resultant economy in manufacture; by its durability and sturdiness, and by its reliability and effectiveness in operation. My improved mechanism comprises a relatively few number of parts, each of which may be economically made, and each of which is of itself strong and durable. These parts may be assembled with readiness and facility, and repairs, if such are necessary, may be easily and quickly made.

85

Other objects will be in part obvious and in part pointed out more in detail herein-after.

The invention accordingly consists in the features of construction, combination of elements and arrangement of parts which will be exemplified in the construction herein-after set forth and the scope of the application of which will be indicated in the appended claims.

90

The invention consists generally in a trigger mechanism having a trigger and a connector associated with and operated by the trigger for engaging the sears in succession upon successive intentional pulls of the trig-

100

ger, the connector being so arranged that, after one barrel is fired, and upon forward rebound of the gun from the shoulder, the connector automatically is thrown out of operation with respect to the sears so that, in case of "involuntary pull" during the jump of the gun, firing of the second barrel is absolutely prevented; the arrangement, however, being such that, after the first barrel is fired, the trigger mechanism is automatically advanced to a position where the second barrel may be intentionally fired as quickly after the first barrel has been fired as any shooter may desire.

15 In the accompanying drawing, wherein I have shown, for illustrative purposes, one embodiment which the present invention may take, it being understood that this disclosure is by the way of exemplification only 20 and my improvements may be incorporated in guns of various kinds and types and in connection with firing mechanisms of various styles and forms:

Figure 1 is a side elevational view of my improved arrangement with both of the hammers in cocked position and the connector in position to actuate the left hand sear upon the first pull of the trigger;

Fig. 2 is a view similar of Fig. 1 but showing in full lines, the left hand hammer as having been fired and the connector as having moved to the position to actuate the right hand sear upon the second pull of the trigger; the inertia element and connector being also shown by dash and dot lines in the position which they have during the period of "involuntary pull";

Fig. 3 is a sectional view taken centrally and longitudinally through the mechanism;

40 Fig. 4 is a detail view taken substantially on line 4—4 of Fig. 1;

Fig. 5 is a sectional view taken on line 5—5 of Fig. 1;

45 Fig. 6 is a perspective view of the sears, connector and shifter, the connector being in position to release the right hand sear on the first pull of the trigger; and

Fig. 7 is a top plan view, on an enlarged scale, of the platform of the safety device 50 and the guide plate 50.

Referring to the drawing in detail, 10 designates the frame of the gun, the same being shown more or less diagrammatically as it may be of any suitable construction and the particular form and shape thereof form no part of the present invention. The firing mechanism includes a pair of hammers 11 and 12 pivoted as at 13. Respectively associated with these hammers are the 55 sears 14 and 15 which may be of any suitable construction and which may be located as desired depending upon the form and position of the hammers themselves. The sears are pivoted on a pin. Each of the 60 hammers is normally urged into firing posi-

tion by a spring such as a spring 9. Each of the hammers has, on its outer face, a notch 16 which is adapted to be engaged by a tooth 17 on the respective sear for holding the hammer in cocked position.

70 The sears are normally urged into engagement with the hammers by springs 18 which may be of any suitable form. Each sear has a tail or rear end provided with a depending projection 19, these projections being adapted to overlie the respective fingers of the connector, as hereinafter described more in detail.

75 The numeral 25 designates the trigger which may be of any suitable construction 80 and which, in the present instance, is pivoted adjacent its forward end on a pin 26. This trigger has a recess 27 forming a socket in which the lower end of the connector is adapted to engage.

85 The connector may be of any suitable form or construction insofar as certain aims of the invention are concerned but, by preference, it is of the novel arrangement disclosed in the drawing and which arrangement will permit of selectability as to which barrel will be fired first, as desired. In the present illustrative disclosure, the connector, which is designated generally by the numeral 90 30, is in the form of a stem, the lower end 31 of which is pointed and engages in the socket 27 of the trigger. The upper end of the connector is more or less fork shaped so as to provide a pair of fingers 32 and 33 which are adapted to engage the projections 19 of 95 the sears in the proper order upon successive pulls of the trigger. The forward finger 32 is the one which results in the release of a sear from its hammer upon the first pull of the trigger, and the rearward finger 33 results in the other sear being released upon the 100 next pull of the trigger. The stem of the connector is non-circular or has flattened sides, as at 34, for a purpose which will be later described. The connector is normally urged forwardly towards the hammers and to its seat on the trigger by a spring 35 about a plunger 36, the lower end of which is seated in a recess or socket 37 in the stem of the connector. The upper end of the plunger is guided in an opening 38 in the top of the carriage which will be hereinafter described.

105 Extending laterally from the connector adjacent its lower end is a fin 39 engaging in a V-shaped notch 40 in the shifter 41 mounted for sliding movement in a slot in the bottom tang of the frame 10 and alongside of the trigger. The shifter has a knurled or roughened surface 42 against which the finger or thumb 110 may be pressed when it is desired to move the shifter from one position to another. The forward end of the shifter may have a notch 43 for receiving the pin 26, and the rear end of the shifter may be guided by the bottom 115 tang of the frame.

When the trigger is in unpulled condition, the fin 39 on the connector engages in the root of the notch 40 and thus the connector is prevented from accidentally shifting from one position to another about its longitudinal axis. When the trigger is pulled, however, this fin is raised in the notch 40 and, unless some means were provided, there is a possibility that the connector would accidentally shift. In order to guard against this, there is provided a guide plate 50 which the fingers 32 and 33 of the connector are adapted to straddle when this connector is raised upon pull of the trigger. This plate 50 is located between the sears and is held in place by the pin 14' on which the sears 14 and 15 are pivoted. The upper edge of the plate engages in a groove 51 in the under side of the upper tang. The lower edge of the plate 50 has a notch 52 to permit the forward finger 32 of the connector to pass through so that that finger can move from one sear to the other. Also, this plate prevents the connector from being shifted accidentally or otherwise when either or both of the hammers have been fired for, in such instance, neither of the fingers 32 or 33 are in registry with the notch 52.

In order to hold the shifter in each of its selected positions, any suitable means may be provided but, by way of example, I have shown the shifter as having a pair of laterally extending holes 55 in which is adapted to selectively engage a pin 56 behind which is a spring 57 housed within a hollow screw 58 threaded into the lower tang. The trigger is cut away or notched at 59 so as to accommodate the screw. The hollow screw serves as a stop for limiting the extent of pivotal movement of the trigger 25, both up and down.

Reference will now be had to the means for preventing "doubling" due to involuntary pull. In accordance with the present invention, an inertia element is so associated with the connector that the latter will lag behind the gun upon the rebound of the latter. This inertia element has an inertia block 60 to the forward end of which is connected a part 61 which, for convenience in terminology, may be called a carriage. The block 60 is of cylindrical form and is located for sliding movement in a tube or barrel 62 projecting rearwardly from the frame 10. The forward end 63 of the block is of reduced diameter and projects through an opening in the rear wall 55 of the frame. By reducing the forward end of the block, a shoulder 65 is provided which serves to limit the forward movement of the block under the influence of the spring 66 located behind the block and engaging against a screw 67 which closes the rear end of the tube 62. The carriage 61 may be pinned to the forward end of the block, as shown, and has an opening 68 through which the connector extends and in which the connector has a limited relative movement under certain con-

ditions. The width of this opening is such as to limit the turning movement of the connector and to give a firm bearing to the connector in its vertical movements. The spring 35 urges the connector against the forward edge 69 of this opening.

The arrangement is such that, when either, or both of the hammers is moved from discharged to cocked position, that movement results in the connector being returned to its initial position (shown in Figs. 1 and 3) so that, when the trigger is pulled, that sear which has been selected for the first firing will be released. Pivoted on a longitudinally-extending horizontally disposed pin 75 in the forward lower end of the carriage is a member 76 which, for convenience, may be termed a positioning cam. The forward edge of this cam is generally V-shaped in cross-section and is adapted to be engaged by the rear end of the hammers. The rear ends of the hammers, substantially abut and their meeting edges are oppositely bevelled, as at 77, so as to form a V (when both of the hammers are cocked) in which the forward edge of the cam 76 engages. (See Fig. 4).

In describing the operation of the trigger mechanism, it may be assumed that it is incorporated in a gun of the over-and-under type and that the over barrel is associated with the left hand sear and the under barrel with the right hand sear. Assuming that it is desired to fire the shell in the over bore first, the shifter will be moved to its rear-most position so as to bring the connector to the position shown in Figs. 1 and 3 of the drawing and in which position the finger 32 is immediately beneath the projection 19 of the left hand sear 14. When the trigger is pulled, the connector is raised so that the finger 32 will raise the left-hand sear, thus releasing the left hand hammer whereupon, after release of the trigger, the parts will move to the position shown by full lines in Fig. 2. It will be noted that the connector is moved forwardly so that the rear finger 33 is now beneath the projection 19 of the right hand sear 15 so that, when the trigger is again pulled, the under barrel is fired. It will be further observed, as heretofore stated, that, when the trigger is raised, the fingers 32 and 33 are brought in straddling relation to the guide plate so that the connector cannot be accidentally turned or shifted by the jar of the gun. The connector can only be shifted for purposes of selectability when it is in the position shown in Figs. 1 and 3 and in which position the forward fingers 32 may move through the notch 52 when the shifter is moved longitudinally. It is further to be noted that, when the trigger is pulled the first time, as just described, the connector is raised and the rearmost finger 33 of the connector will be behind and in the plane of the right hand sear so that, if the trigger is held,

in pulled condition, this finger will engage against the rear end of that sear and thus the connector will be positively held against assuming the operative position shown by full lines in Fig. 2, until the trigger is released. In other words, the rear end of the sear and the rearmost finger constitute, so to speak, means for preventing full forward movement of the connector while the trigger is held in pulled condition upon firing of the first barrel. This arrangement is of advantage in that it further guards against involuntary pull and relieves certain of the parts of certain strains which might otherwise result.

When the left hand hammer 11 has been discharged, the support for the cam 76 is thus removed and the cam, due to its V-shaped edge and level surface 77 of the right hand hammer, may swing to the left, whereupon the inertia block, under the influence of the spring 67 behind it, will move, together with the connector, to the position shown in Fig. 2. When the gun is broken, the usual cocking lever (not shown) will cock the left hand hammer and, while that hammer is swinging rearwardly and downwardly, it will engage the cam 76 and thus move the inertia block, together with the connector, back to the initial position shown in Fig. 1. The right hand hammer operates in a similar manner.

“Doubling,” the cause and effect of which have been previously described, is avoided and, in fact, entirely guarded against by the action of the inertia element on the connector. It will be remembered that the connector engages the forward edge 69 of the opening 68 in the carriage 61 so that, upon rebound of the gun, the connector cannot jump forwardly of the inertia block. On the forward rebound of the gun, the inertia element, due to its mass, will lag behind the gun. Also the connector will be caused by the inertia block to lag behind the forward movement of the gun and, during this extremely brief period, the connector is held out of operative position with respect to the sears, as is shown by the dash and dot lines in Fig. 2. If, during this interval and during the rebound of the gun, the trigger, which has jumped away from the finger of the shooter on the recoil of the gun, should again re-engage the finger resulting in an unintentional pull of the trigger, the second sear will not be operated. The timing is such that the connector is held by the inertia of the inertia block out of operative relation to the sears during that period in which the trigger and finger are likely to be re-engaged, that is to say, the inoperative position of the connector and the involuntary pull coincide. It will be observed, however that while doubling, due to involuntary pull, is absolutely guarded against, the trigger mechanism may assume its firing position (shown by full lines in Fig. 2) relative to the second sear immediately after the danger of

involuntary pull has passed so that the two barrels may be intentionally shot in as rapid succession as is humanly possible. There is no chance of “balking.” It will further be observed that, since the inertia of the inertia element alone is relied upon to automatically delay the repositioning of the connector with respect to the sear after the first barrel is fired, and to cover the interval in which involuntary pull and doubling take place, the trigger pull can be made as light as desired bearing in mind only what would be a sufficiently secure engagement between sears and hammers to prevent one sear being jarred off when the other sear is fired. It will still further be observed that the inertia block is mounted for rectilinear movement and that that block is not supported on or carried by the connector. The connector and the trigger are of relatively light weight and, as these two parts are the only parts that can bear on the sears in a direction to disengage the same, there is little possibility of those parts disengaging the sears in the event that the gun should be severely jarred, as would be the case if it were dropped onto the ground in an upside down condition.

The safety mechanism shown in the drawing has certain features of novelty and advantage which will now be described. Slidably mounted on the top tang of the frames is a safety latch having a thumbpiece or plate 90 and a depending web 91 extending through a slot in the tang. The lower edge of this web in the “off” position lies forwardly of the upper end of the plunger 36 which, as stated, is associated with the connector. The “off” position is shown in the Figs. 1 and 2. When the safety latch is in the safe position shown in Fig. 3, the web is immediately above the upper end of the plunger 36 so that the trigger cannot be pulled. Pivoted to the web by a pin 92 is a U-shaped platform 93 having, at its free ends, projections or lugs 94 which are adapted to selectively engage in notches 95 and 96 on the under side of the upper tang. The platform is normally urged in a direction to engage the lugs 94 against the under surface of the tang by a spring 97, the forward end of which passes through an opening 115 in a depending web 98. The extreme forward end of the spring is turned upwardly and is adapted to resiliently engage in an opening 99 in a horizontal web 100. These webs 98 and 100 are formed by a generally L-shaped projection extending laterally from the side of the guide plate 50. It will be observed that this arrangement is very simple and effective.

As many changes could be made in the above construction and many apparently widely different embodiments of this invention could be made without departing from the scope thereof it is intended that all matter contained in the above description or shown

in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In combination, hammers, sears respectively associated therewith, a trigger mechanism including a connector through which said sears are successively operated upon successive intentional pulls of the trigger and an inertia block supported for movement otherwise than on said connector and associated with said connector for maintaining the same out of operative relation to the sears during the forward rebound of the gun.

2. In combination, hammers, sears respectively associated therewith, a trigger mechanism including a connector adapted to move forwardly from operative position with respect to one sear to operative position with respect to the other sear, and an inertia element to which said connector has relative movement and adapted to engage and hold said connector in inoperative position with respect to the sears during the period of involuntary pull.

3. In combination, hammers, sears respectively associated therewith, a trigger mechanism including a connector through which said sears are successively operated upon successive intentional pulls of the trigger, and an inertia element mounted for rectilinear sliding movement longitudinally of the gun and having a face against which said connector is adapted to engage whereby said connector is held against movement into operative position with the successive sear during the period of involuntary pull.

4. In combination, a frame, hammers within the frame, sears respectively associated with the hammers, a trigger mechanism including a connector through which said sears are successively operated upon successive intentional pulls of the trigger, and an inertia element slidably supported by said frame and having a part through which said connector extends, said inertia element being arranged to engage said connector and hold the same in inoperative relation to the sears during the period of involuntary pull.

5. In combination, a frame, hammers, sears respectively associated with the hammers, a trigger mechanism including a connector through which said sears are successively operated upon successive intentional pulls of the trigger, an inertia element supported by the frame and associated with said connector for holding the same in inoperative position with respect to the sears during the period of

involuntary pull, and a spring normally urging said inertia element forwardly.

6. In combination, hammers, sears respectively associated therewith, a trigger mechanism including a connector through which said sears are successively operated upon successive intentional pulls of the trigger, a slidably mounted inertia element having an inertia block and a carriage, said carriage being adapted to engage said connector to hold the same in inoperative position with respect to the sears during the period of involuntary pull, a plunger having one end engaging said connector and the other end slidably guided by said carriage, and a spring about said plunger and bearing against said carriage.

7. In combination, hammers, sears respectively associated therewith, a trigger mechanism including a connector through which said sears are successively operated upon successive intentional pulls of the trigger, an inertia element associated with said connector for holding the same in inoperative position with respect to the sears during the period of involuntary pull, means for normally urging said inertia element forwardly, and cooperating means between said hammers and inertia element for retracting said inertia element and moving therethrough said connector to initial position when either or both of said hammers are moved to cocked position.

8. In combination, hammers, sears respectively associated therewith, a trigger mechanism including a connector through which said sears are successively operated upon successive intentional pulls of the trigger, an inertia element associated with said connector for holding the same out of operative relation to the sears during the forward rebound of the gun, and a member carried by said inertia element, said hammers having faces adapted when either or both of the hammers are moved to cocked position to engage said member and being arranged, when either hammer is discharged, to disengage from the cocked one and follow the one discharged.

9. In combination, hammers having on their rear ends adjacent inclined surfaces forming a V groove, sears respectively associated therewith, a trigger mechanism including a connector through which said sears are successively operated upon successive intentional pulls of the trigger, a slideable inertia element adapted to engage and hold said connector in inoperative position with respect to the sears during the period of involuntary pull, a spring urging said element forwardly and a transversely movable cam carried by said element and having an edge adapted to engage in said groove when both of said hammers are cocked.

10. In combination, a pair of hammers, a sear for each hammer, a single trigger, a

connector supported by said trigger and arranged to successively actuate said sears on repeated pulls of the trigger, said connector being adjustably supported whereby the same may be selectively set so that the sears will be operated in the desired order on repeated pulls of the trigger, means for selectively setting said connector, and an inertia element adapted to engage and hold said connector in inoperative position with respect to the sears during the period of involuntary pull.

11. In combination, a pair of hammers, a sear for each hammer, a single trigger, a connector supported by the trigger and arranged to successively actuate said sears upon repeated pulls of the trigger, a shifter associated with said connector for selectively setting the same relative to said sears, and an inertia element supported for sliding movement and adapted to engage said connector and hold the same against forward movement during the period of involuntary pull, said element also constituting means for in part guiding said connector.

12. In combination, a pair of hammers, a sear associated with each hammer, a single trigger, a connector supported by the trigger for turning movement from one position to another to allow of selectability of the order in which the barrels are fired, and an inertia element arranged to engage said connector and hold the same in inoperative position with respect to the sears during the period of involuntary pull, said element having a part provided with an opening through which said connector extends and in which said connector has relative movement with respect to said element.

13. In combination, hammers, sears respectively associated therewith, a single trigger, a connector through which said sears are successively operated upon successive intentional pulls of the trigger, said connector being supported by said trigger for turning movement to allow of selectability of the order in which the barrels are fired, an inertia element associated with said connector for maintaining the same in inoperative position with respect to the sears during the period of involuntary pull, and cooperating means between said hammers and inertia element whereby said element is retracted and the connector is moved to initial position when the hammers, either singly or together, are moved to cocked condition.

14. In combination, a pair of hammers, a sear for each hammer, a single trigger, a connector mounted on said trigger for selective adjustment relative to the sears so that the latter will be operated in the desired selected order on repeated pulls of the trigger, a shifter for selectively adjusting said connector and means independent of the hammers, sears and shifter for pre-

venting shifting of the connector from one selected position to the other when it is in pulled condition.

15. In combination, a pair of hammers, a sear for each hammer, a single trigger, a connector mounted on the trigger and arranged to successively actuate said sears on repeated pulls of the trigger, said connector being supported for selective adjustment relative to the sears so that the latter will be operated in the desired selected order on repeated pulls of the trigger, a shifter for selectively setting said connector, and a fixed plate cooperating with the upper end of said connector for preventing shifting of said connector in all positions of said connector and trigger, except when the connector is in initial position and the trigger is unpulled when the connector is in that position.

16. In combination, a pair of hammers, a sear for each hammer, a single trigger, a connector supported by the trigger and arranged to successively actuate said sears on repeated pulls of the trigger, a shifter associated with said connector for selectively setting the same relative to said sears so that the latter will be operated in the desired selected order on repeated pulls of the trigger, said shifter preventing accidental shifting of the connector when the trigger is in unpulled condition, a fixed plate, and a pair of fingers on said connector and adapted to engage said sears, said fingers being in straddling relation to said plate when said trigger is pulled.

17. In combination, a pair of hammers, a sear for each hammer, a single trigger, a connector supported by the trigger and having a pair of fingers adapted to engage said sears, a shifter for selectively setting said connector so as to adjust the fingers in the desired relation to said sears, said shifter preventing accidental shifting of the connector when the trigger is in unpulled condition, and a plate above said connector and having a notch permitting shifting of said connector when the connector is in initial position and the trigger is unpulled, said fingers being in straddling relation to said plate and out of registry with said notch in all of the positions of said connector.

18. In combination, a pair of hammers, a sear for each hammer, a single trigger, a connector carried by the trigger and arranged to successively actuate said sears on repeated pulls of the trigger, a slidably mounted inertia element adapted to engage said connector and hold the same in inoperative position with respect to the sears during the period of involuntary pull, a spring pressed plunger engaging said connector and slidably guided by said element, and a safety device adapted, when in safe position, to lie

above said plunger and prevent actuation of the trigger.

19. In combination, hammers, sears respectively associated therewith, a trigger, a connector supported thereby, a slidably mounted inertia element having an inertia block and a carriage, said carriage being adapted to engage said connector to hold the same in inoperative position with respect to the sears during the period of involuntary pull, a plunger having one end engaging said connector and the other end slidably guided by said carriage, a spring about said plunger, and a slidable safety device having a portion adapted to lie, when the safety device is in safe position, in the path of movement of said plunger so as to hold the same and the trigger against actuation, said portion being removed from the path of travel of the plunger when the safety device is in "off" position.

20. In combination, a frame having a lower tang provided with a slot, a trigger in said slot, a pin on which said trigger is pivoted, a connector supported by the trigger from turning movement, a shifter alongside of said trigger and mounted for sliding movement in said slot; and means for holding said shifter in each of its adjusted positions and including a pair of recesses in said shifter, a spring pressed plunger adapted to engage in said recesses and a screw carried by said tang extending into said slot and supporting the spring and plunger, said screw constituting means for limiting the extent of pivotal movement up and down of said trigger.

21. In combination, hammers, sears respectively associated therewith, a trigger mechanism including a connector adapted to move forwardly from operative position with respect to one sear to operative position with respect to the other sear, an inertia element movable forwardly with said connector and adapted to hold said connector in inoperative position during the period of involuntary pull, and means for preventing said inertia element and connector from moving forwardly while the trigger is held in pulled condition upon firing the first barrel.

22. In combination, a pair of hammers, a sear for each hammer, a single trigger, a connector supported by said trigger and having a pair of fingers adapted to engage said sears, and an inertia element mounted for rectilinear sliding movement longitudinally of the gun and constituting guiding means for the connector when the trigger is pulled, said inertia element and connector being movable forwardly and rearwardly of the gun due to inertia, one of said fingers being arranged to engage the rear end of the unfired sear while the trigger is held in pulled condition after firing the first barrel.

JOHN BROWNING.
